[57] **ABSTRACT**

A splinter shell and method of making same according to which at least two tubular bodies of strong but deformable material are coaxially arranged with regard to each other and located one within the other while being peripherally spaced from each other by the diameter of the desired splinter bodies to be incorporated in the shell, whereupon the splinter bodies are introduced between the tubular bodies and, while the outermost tubular body is confined on its outside, the inner peripheral surface of the innermost tubular body is subjected to radially outwardly directed pressure to cause all of the tubular bodies to deform partially around the splinter bodies and to sandwich the same between the adjacent tubular bodies.

METHOD OF MAKING SPLINTER SHELLS, AND SPLINTER PROJECTILES AND SPLINTER HEADS MADE ACCORDING TO THIS METHOD

The present invention relates to a method of making splinter shells while using preformed, preferably ball-shaped or pellet-like splinters, and also concerns splinter projectiles and splinter heads made according to this method.

It is known so to prenotch explosive bodies by longitudinal and transverse cuts that they will be split up into individual splinters during the detonation of the explosive charge. In addition thereto, it is also known to bring about this effect by the insertion of a preshaped foil upon the surface of the explosive charge. Aside from the fact that the power required for splitting up such explosive bodies considerably reduces the effective force of the splinters, the just mentioned steps do not bring about the formation of splinters of a defined size and also fail in furnishing the desired penetration and uniform scattering in all directions.

A better splinter effect and distribution can be realized with preformed splinters which are filled, for instance, into a form and are embedded in a hardening skeleton of concrete, synthetic material, or the like.

Thus, for instance, it has become known to arrange preformed pellets or ball-shaped splinters on an explosive body in one or more layers. In such an instance, the pellets are interconnected by a pourable resin or the like and form a more or less resistant splinter shirt or screen. Inasmuch as such baked together splinter shirt is able to absorb only small axial forces and nearly no radial forces, the employment of such splinter shirt is customarily limited to throwable ammunition and to rockets with a low number of twists. For the employment of such splinter shirt in connection with projectiles, there is required not only a shell frame but also a mantle which is able to absorb the occurring forces. This means that on one hand additional mass has to be carried which does not contribute to the splinter effect, while on the other hand, as mentioned above, the output of the explosive charge is reduced. While by the employment of preformed splinter pellets the hit density of splinter projectiles is considerably increased, the embedding of the splinter pellets as well as the mantle or jacket lead to an undesired reduction in the penetrating capability.

It is, therefore, an object of the present invention so to deform preformed splinters together with the projectile or fighting head shell that a splinter mantle will be created which, while being able to overcome the shearing and torsion forces occurring during the firing, will nevertheless by the explosive charge without high losses in output be split up completely into splinters of a defined size and number and of a high piercing capability as well as a predetermined scattering range.

This object and other objects and advantages of the invention will appear more clearly from the following specification in connection with the accompanying drawing, in which:

FIG. 1 is a side view of a twist projectile, partly in section.

FIG. 2 is a cutout of a one-layer splinter shell prior to its high pressure deformation.

FIG. 3 is a partial cutout of FIG. 2 after plating the tubes upon each other.

FIG. 4 is a partial cutout of a two-layer splinter shell prior to its high pressure deformation.

FIG. 5 shows the same cutout as FIG. 4 but following the high pressure deformation.

FIG. 6 illustrates splinter elements as they are formed by the explosion of a splinter shell produced according to the method of the present invention.

The problem underlying the present invention has been solved by a method which is characterized primarily in that a metallic projectile tubular body of the

desired outer diameter is introduced into a cylindrical slightly conical hollow tool mold which has an inner diameter corresponding to the outer diameter of the splinter shell to be produced, while a second metallic tubular body having an outer diameter which is smaller than the inner diameter of the outer tubular body by twice the maximum diameter of the splinters is centrally inserted into the first tubular body. Thereupon the splinter filling is poured into the thus formed tubular cylindrical chamber, and finally by high pressure deformation the inner tubular body is by pressing its walls in between the splinters deformed radially outwardly with regard to the rotation symmetric splinter shell and together with the outer tubular body is plated so as to form a rotation symmetric splinter shell with a splinter mantle arranged in the boundary region of the tubes.

In this way a one-layer or a multi-layer splinter mantle may be produced. For making multi-layer splinter bodies, for instance, two or more tubes which are narrower by twice the splinter diameter are centrally arranged one within the other. The tubular cylindrical hollow chambers are then filled with splinter bodies and the tubes are plated upon each other while fully enclosing the splinters and while simultaneously pre-fragmenting the tubes into splinter elements of a predetermined size and mass.

Referring now to the drawing in detail, the twist projectile 1 comprises a splinter shell 2 forming the projectile mantle which houses an explosive charge 3 adapted to be ignited by a fuse 4. As will be seen from FIG. 2, the splinter shell 2 in its initial manufacturing condition comprises an outer tube 6 of deformable metal, for instance extra strong aluminum or steel, with a wall thickness of, for instance, 3 mm, a layer of preformed pellet splinters 7 of ceramic (Al_2O_3) or hard metal, such as tungsten carbide, iron-titanium-alloy, or the like with a diameter of, for instance, 4 mm, and a metallic inner tube 8 of, for instance, a 5 mm wall thickness. The splinters 7 may, if desired, also have a shape differing from the shape of a sphere, for instance, may be roller-shaped. It is important in this connection that the hollow chamber 5 between the tubes 6 and 8 is uniformly filled with one layer of splinters 7.

For manufacturing the splinter shell 2 according to FIG. 3, the tubes 6 and 8 are interconnected in conformity with the above described method. The radial deformation may be effected in a manner known per se and, more specifically, in a shock-like manner, for instance, by explosion deformation or electromagnetically, but it may also be effected, if desired, by pressing, namely by driving a conical calibrating bolt through the inner tube 8. In this way not only the splinters 7 are on all sides enclosed in the tubes 6, 8, but at the same time the tubes 6, 8 are differently compacted and deeply prenotched. In this way a grate of coherent splinters of defined magnitude is formed which surrounds the pre-shaped pellet splinters 7 in the manner

of a cartridge case base and during the detonation of the explosive charge 3 not only frees the pellet splinters 7 but also is itself split up into substantially uniform splinters 11 (FIG. 6).

According to FIGS. 4 and 5, the splinter shell may also consist of a plurality of layers in which instance the manufacturing process corresponds to that described above. In addition to the tubes 6 and 8, an additional inner tube 10 is provided. A further layer of pellet splinters 7 is filled into the tubular hollow chamber 9. As will be seen from FIG. 5, also in this instance, after the high pressure deformation, the pellet splinters 7 are fully pressed into the tubes 6, 8 and 10 and these tubes are prenotched in a grate-like manner.

FIG. 6 shows the size of the broken up splinters 11 with regard to the pellet splinters 7.

By the employment of tubes of extra or highly strong materials and by their additional compacting during the transformation process, not only the pellet splinters 7 but also the broken pieces or splinters 11 of tubes 6, 8 and 10 will obtain a high piercing capability.

As will be seen from the above, the method according to the present invention makes it possible to produce splinter shells which comprise two or more tubes which are plated upon each other and which by means of the enclosed pellet splinters are pre-fragmented and encase one or more layers of pellet splinters. These splinter shells will then be able, when applied to twist projectiles, to withstand the shearing and centrifugal forces occurring during the firing process. Therefore, they are able directly to form the mantle of the projectile. Inasmuch as the tubes are during the high pressure deformation prefragmented in a grate-like manner by the pressed-in hard metal pellet splinters and are differently compacted and are thus subdivided into a coherent grate of splinter elements, it will be assured that during the detonation of the explosive charge not only the pellet splinters will be freed but also the tubes will be split-up into many substantially uniform splinters of a predetermined size which with a defined piercing capability are sprayed over a limited range.

It is, of course, to be understood that the present invention is, by no means, limited to the method set forth above and the splinter bodies shown in the drawing but

also comprises any modifications within the scope of the appended claims.

What I claim is:

1. A method of making a splinter shell for use in projectiles, which includes the steps of: preparing a first metallic tubular body to form the outer wall of the splinter shell to be made, inserting into said first tubular body a second metallic tubular body of an outer diameter less than the inner diameter of said first tubular body by substantially twice the maximum diameter of the splinters to be incorporated into said shell while arranging said second tubular body coaxially with said first tubular body, filling splinters into the thus formed annular chamber defined by said first and second tubular bodies, and while holding said first tubular body confined on its outer peripheral surface subjecting the inner peripheral surface of said second tubular body to radially outwardly directed pressure so as to press said first and second tubular bodies partially into said annular chamber and sandwiching said splinters between said first and second tubular bodies.

2. A method according to claim 1, which includes the step of inserting into said second tubular body at least one additional metallic tubular body coaxial with said second tubular body and circumferentially spaced from said second tubular body by a distance substantially equaling the diameter of splinters to be placed between said second and said additional tubular body, introducing splinters into the thus formed annular chamber defined by said second and said additional tubular body, and while holding said first tubular body confined on its outer peripheral surface subjecting the inner peripheral surface of said additional tubular body to radially outwardly directed pressure so as to press said additional tubular body and said second tubular body partially into the annular chamber defined by said second and additional tubular bodies and sandwiching the splinters therein between said last mentioned two annular bodies simultaneously with the sandwiching of the splinters in said first mentioned annular chamber between said first and second tubular bodies.

3. A method according to claim 1, which includes the step of pre-fragmenting the tubular bodies.
